CONTROL CONSOLE FOR AN APPLIANCE
David D. Sheeley, Harper Woods, Mich., assignor to
General Motors Corporation, Detroit, Mich., a corpora-
tion of Delaware
Filed May 16, 1960, Ser. No. 29,312
2 Claims. (Cl. 240—2)

This invention relates to a domestic appliance and more particularly to a pivotally mounted lamp housing for a control panel.

The trend in modern home design is to install many of today's major appliances in the kitchen area or in areas frequently entered by visitors to the home. Consequently, these appliances are accessible to small children and exposed to the view of visitors. Laundry appliances in particular are installed in such places and the control panels thereof impart a rather mechanized character to the area.

Accordingly, it is an object of this invention to provide a domestic appliance with a lamp housing which is effective in one position to illuminate the controls and effective in another position to illuminate the room in which the appliance is installed.

A further object of this invention is to provide a control panel for a domestic appliance with a cover which may be pivotally positioned to conceal such control panel.

It is also a general object of this invention to provide a control panel which may be easily serviced from the front thereof.

A more specific object of this invention is the provision of a lamp housing for a control panel which is yieldingly latched in a raised position to illuminate the control panel and yieldingly resistingly pivoted to a lowered position for concealing the control panel.

Further objects and advantages of the present invention will be apparent from the following description, reference being had to the accompanying drawings wherein preferred embodiments of the present invention are clearly shown.

In the drawings:

FIGURE 1 is a fragmentary perspective view of a domestic appliance having a pivotal lamp housing in its closed position;

FIGURE 2 is a fragmentary perspective view of a domestic appliance having a pivotal lamp housing in its open position;

FIGURE 3 is a sectional view of a control housing with its lamp housing in raised position taken generally along line 3—3 in FIGURE 2;

FIGURE 4 is a sectional view taken along line 4—4 in FIGURE 3.

In accordance with this invention and with reference to FIGURE 1, a domestic appliance 10, such as a clothes washer, is illustrated. The appliance 10 has a cabinet 12 closed at the top thereof by a hinged door 14. Disposed on the top of the cabinet 12 is a combination control and lamp housing or console shown generally at 16. The console 16 is comprised of a control housing 18 and an upper lamp housing or cover portion 20. Disposed at each end of the control housing 18 is a metal die cast control housing end frame 22, 23, each of which includes an upper lamp housing support wall portion 17 which merges with an inwardly sloping integral lower wall portion 19. Each wall portion 17 has a pin 24 on which the upper lamp housing 20 is pivotally mounted for movement between a raised position shown in FIGURE 2 and a lowered position shown in FIGURE 1. In the raised position of the upper lamp housing 20, a control panel 26 is uncovered to reveal a plurality of control knobs, such as 28, and cycle selecting buttons, such as 30. Since the

2

upper lamp housing 20 is cut out to expose a translucent panel portion 32 on its underside and another translucent panel portion 34 on the top thereof, the lamp housing is effective in the arrangement of FIGURE 1 to illuminate the area surrounding the appliance. With the lamp housing 20 in its raised position of FIGURE 2, the translucent wall 32 illuminates the control panel 26.

Turning now to FIGURE 3, the structure will best be understood. Since each control housing end 22, 23 is the mirror of the other, an explanation of the end 23 will suffice for both. The control housing end may be die cast and includes horizontal bottom flanges 49, 42 which rest on the top of the cabinet 12 to receive fastening means, such as 44, for holding the control housing ends to the cabinet. The end housing 23 includes also an integral boss 46, 48 for supporting a transverse U-shaped control support channel 50 which extends from one control housing end 22 to the other housing end 23. Fastening means, such as bolts 52, are used to secure this elongated channel and to add transverse stability to the upstanding control housing ends 22 and 23. The integral upstanding front and back legs 68 and 78 of the U-shaped support channel are formed with shoulders 56, 54, respectively, to receive a glass or plastic panel 58 through which the control indicia may be selectively visible. Note that the control switch means, such as 60, are fastened to the underside of the bottom wall 62 of the support channel 50, the control knob 28 extending through the panel 58 as well as the channel wall 62.

For retaining the control panel 58 on the shoulders 54 and 56, a rear trim strip 64 coextensive with the support channel 50 is fastened, as at 66, to the leg 68 of the channel 50. At the front of the control housing 18, a second trim strip 70 forms the front wall thereof and seats at each end on a notched out shoulder 72, 74 in the lower wall portions 19 of the respective control housing end frames 22, 23. The trim strip 70 forms a smooth coplanar front wall for the control housing with the end frames 22, 23 and is held in place by screws 76 which extend into fastening engagement with the upstanding leg 78 of the support channel 50. Note that the trim strip 70 has a top flange 80 which overlies the front edge of the control panel 58 to hold it in position on the shoulder 54. It is thus seen that access is gained to the controls simply by removing the screws 76 and the front trim 70. After removing the knobs, such as 28 and 30 and the control panel 58, the entire support channel 50 is removable simply by unscrewing the fastening means 52. Consequently, any of the control switches, such as 60, may be serviced in this manner from the front of the appliance. The rear of the control housing is closed by a straight sheet metal rear panel 82 which may also be fastened in any suitable manner to the end housings 22 and 23.

With further reference to FIGURES 2 and 3, an explanation of the construction for the lamp housing portion will be set forth. The upper lamp housing 20 has a die cast frame which forms a right-hand end wall 90 and a left-hand end wall 92 interconnected by an integral front attachment flange or transverse strut 94 and a rear lamp housing wall 96 from which is spaced a parallel transversely extending rib or web 98. The rear wall 96 of the upper lamp housing and its spaced webbing 98 forms a U-shaped channel 100 in which electrical conduits may be disposed for a fluorescent tube 102 which may be supported at its opposite ends on the lamp housing end walls 90, 92 in any conventional manner. An opening (not shown) in the bottom of the channel 100 will be used for directing the lamp wiring into the control housing. The upper lamp housing casting is also formed with transversely extending shoulders 104 and 106 which extend from end wall 90 to end wall 92 to support an

upper reversely bent translucent lamp shade 108. An elongated or transverse bracket 109 anchors one end of the shade on the shoulder 106. If necessary a similar bracket (not shown) may be fastened to the cast frame to tie down the free end of the shades top side. The shade 108 is made of semi-opaque methyl methacrylate and is bent double to define the control panel illuminating portion 32 and a diametrically opposite illuminating portion 34 for lighting up the appliance area when the lamp housing is closed. Note that the cast frame of the upper lamp housing is formed with a window or opening 110 between the shoulders 104 and 106 to circumscribe or outline the shade portion 32.

For locking the upper lamp housing and the upper lamp shade 108 in attached relationship, a sheet metal upper lamp cover 114 includes an attachment lip or turned over flange 116 which fits or hooks over the housing attachment strut 94 the entire cover then being pivotable into locking engagement with a lamp cover latch piece 118. The lamp cover latch 118 is formed of spring metal having juxtaposed legs 120, 121 which grippingly engage the webbing 98 of the upper lamp housing. The lamp cover latch piece includes also a keeper portion 124 which cooperates with a struck-out tang 126 on the rear wall or turned down flange 128 of the upper lamp cover 114. Thus, with the upper lamp cover attached to the front of the upper lamp housing by the flange 116, the rear wall 128 may be pivoted downwardly, the tang 126 camming the cover latch keeper portion 124 inwardly until it snaps over the hump and locks the upper lamp housing in assembled relationship with the die cast frame. Note how the flange wall 128 merges with the frame wall 96 to form a smooth coplanar surface at the rear of the lamp housing. To release the latch 118 a screwdriver need only be inserted and twisted between the meeting edges of cover wall 128 and casting wall 96. Additional stability is provided for the upper lamp cover 114 at each side thereof by a rib such as 130 which nests along the inner sides of the frame end walls 90, 92 when the lamp housing is assembled. The ribs 130 may be formed with turned-over flanges such as 132 which lay in juxtaposition to the upper lamp cover and may be fastened thereto as by welding along the jointure. A cutout 112 in the upper lamp cover outlines or frames the shade portion 34—the inherent resiliency of the shade causing the shade portion 34 to bear tightly against the underside of the lamp cover.

The user will need access to the control panel 26 to proscribe a desired operating cycle. Consequently, the lamp housing 20 is pivoted to its raised control panel illuminating position. It is necessary that the lamp housing remain in its raised position without falling and, for this reason, a yieldable latch arrangement is provided. Formed on each control housing end casting 22 and 23 is an integral cylindrical socket 140 into which fits a latch bolt 142 biased outwardly by a spring 144. The rear wall 96 of the upper lamp housing is formed with a recess 146 in vertical coplanar relationship to the bolt 142, thereby yieldably latching the lamp housing in its raised position.

When it is desired to position the lamp housing 20 in its lowered position of FIGURE 1, the lamp housing may be grasped at its front edge thereof and lowered into its closed position. It is desirable that there be a certain amount of resistance to this downward motion so that the lamp housing will not drop damagingly on the control panel. For this reason, a brake-type pivot arrangement is utilized at each end of the lamp housing to pivot the lamp housing to the control housing end walls 22 and 23. This braking pivot is shown in section in FIGURE 4 as it applies to the pivot connection between the control housing end wall 23 and the upper lamp housing end wall 92. The control housing end wall 23 is formed with a shouldered aperture 150 which receives a double-headed pivot pin 24 having a threaded portion 154 at one end

thereof. A nylon washer 156 is placed about the pivot pin 24 and interposed between the control housing wall 23 and lamp housing wall 92. Abutting a braking shoulder or embossment 158 on the lamp housing wall 92 is a frictional braking washer 160 of neoprene asbestos or other suitable frictional material. Next, a steel washer 162 abuts the frictional washer 160 and is prevented from relative rotation with the pivot pin 24 by means of a single flat sided portion 164 on the pivot pin. A Bellville spring washer 166 is juxtaposed with the steel washer 162 and in sandwiched relationship with a second steel washer 168 held against rotation by a double-D flat 164, 169 on the pivot pin. The stacked assembly of brake washers and compression washers are retained on the shank of the pivot pin by a nut 170 working in cooperation with a lock washer 172. The nut 170 may be tightened until the desired braking characteristic for the lamp housing pivotal movement is acquired. It should be understood that the same braking pivotal arrangement is used in connection with the pivot pin 24 on the right-hand control housing end wall 22. With this braking arrangement, a slight amount of force is required to lower the lamp housing 20 to its closed position, thereby preventing any dropping or shocking movement on the part of the lamp housing which might damage the lamp 102 therein.

It should now be seen that a novel illuminating arrangement has been provided for an appliance wherein a lamp housing is provided with illuminating surfaces on two sides thereof. One side is effective to illuminate a control panel when the lamp housing is in one position and the other side thereof is effective to illuminate the area surrounding the appliance when the lamp housing is in another or closed position. This arrangement will effect a clean and neat appearance for the appliance when it is not in use and will also protect the controls from manipulation by small children.

While the embodiments of the present invention as herein disclosed, constitute preferred forms, it is to be understood that other forms might be adapted.

40 What is claimed is as follows:

1. In combination with an appliance, a control console having a control housing and a lamp housing, said control housing including a pair of end walls connected to said appliance, a U-shaped support channel interconnecting said end walls, a control panel carried by said support channel, a control fastened to said support channel and having an actuator extending through said control panel, a first trim strip between said end walls and fastened to one side of said support channel for retaining the front of said control panel and for defining a front wall for said control housing, a second trim strip between said end walls and fastened to the opposite side of said support channel for retaining the rear of said control panel, a spring biased detent on one of said end walls, 45 and a pivot pin on each of said end walls for pivotally supporting said lamp housing between raised and lowered positions, said lamp housing including a frame having a front strut and a rear wall and defining a control panel lamp opening, a spring clip attached to said frame adjacent said rear wall, an upper lamp cover coextensive with said frame and having a front flange engaging said strut and a rear flange latchingly engaging said spring clip in a manner to place said frame rear wall coplanar with said rear flange and a U-shaped lamp shade, said lamp cover defining a second lamp opening and restraining said lamp shade between said frame and said cover, said rear wall of said frame having a notch in alignment with said detent for receiving said detent when said lamp housing is in its raised position, and illuminating means in said lamp housing adjacent said lamp openings, whereby said control panel is illuminated when said lamp housing is in said raised position and whereby said control panel is covered and the area surrounding the appliance illuminated when said lamp housing is in said lowered position.
2. In combination with an appliance having a switch,

a control housing for supporting said switch and an upper lamp housing having a frame and an upper lamp cover releasably attached to said frame, said upper lamp cover having an upper lamp aperture, said frame having a lower lamp aperture, illuminating means attached to said frame within said lamp housing, a unitary translucent shade having a first portion adjacent said upper lamp aperture and a second portion adjacent said lower lamp aperture, means on one of said housings adjacent said switch for pivotally supporting said lamp housing between a raised 10 position wherein said switch is exposed and illuminated and a lowered position wherein said switch is substantially completely concealed, detent means on one of said housings cooperating with notch means on the other of said housings for releasably latching said lamp housing in 15

said raised position, and brake means including a spring biased frictional washer on said pivotal support means for resisting the movement of said lamp housing to said lowered position.
